Morris J. Berry, Queens County, N. Y.

Application April 10, 1952, Serial No. 281,527

2 Claims. (Cl. 150—34)

This invention relates to bags and more particularly to formula bags adapted to receive a plurality of formula bottles and to maintain them at predetermined temperatures.

In storing infant formula containers such as baby nursing bottles to be carried from place to place as in traveling, such bottles are often placed in bags especially designed for that purpose. Such bags have been provided with thermal insulation thereby permitting the bottles to be placed in the bag in heated condition for example so that they are ready for use upon removal from the bag. However, it is often required that such bottles be maintained at different temperatures. Thus, for example, although it may be desired to maintain one bottle in heated condition ready for use, the same trip may require that another bottle be maintained in cold condition so as to prevent spoilage.

It is, therefore, an object of this invention to provide a formula bag suitable for carrying formula containers or bottles from place to place and for maintaining each of said bottles at a predetermined temperature.

Another object of this invention is to provide a formula bag wherein bottles may be maintained separate and apart from each other and in such a condition as to prevent physical contact therebetween which might result in the breakage of such containers.

A further object of this invention is to provide a formula bag with a plurality of independent chambers each of which is adapted to receive a nursing bottle or similar container and to maintain each such container or bottle and its contents at a predetermined temperature wherein for example one such container is maintained in warm condition while the other is maintained in a lower temperature.

It is also an object of this invention to provide a formula bag of the character indicated which is adapted to contain a plurality of formula bottles or similar containers at such temperatures as may be required and wherein means are provided for the insertion or removal of each of such bottles independently of one another and without affecting the thermal condition of any other bottle within said bag.

A still further object of this invention is to provide a formula bag of the character indicated which is simple, efficient and may be economically constructed and which is provided with bottle receiving chambers as well as a space or compartment for the reception of other articles all of which may be readily carried from place to place without breakage.

In order to accomplish these and other purposes, I have provided a formula bag of substantially rectangular configuration having independent insulated chambers positioned adjacent the end portions thereof as well as a main compartment extending the entire width of the bag. Provision is also made for access to each of these chambers or the compartment through openings which are provided with separable closure means positioned along the top and end edges of the bag. Independent

2

thermal insulation is provided for each of the end chambers which are spaced from each other so that in addition to maintaining each of the bottles in thermally insulated condition the transfer of heat from one compartment to the other due to possible inefficiency of the insulating material which may be employed is effectively prevented.

These and other objects of my invention, as will hereinafter appear or be pointed out, are attained in the illustrative embodiment of my invention shown in the accompanying drawings wherein:

Figure 1 is a side elevational view of a formula bag in accordance with the present invention,

Figure 2 is a top view showing the bag supporting strap partly broken away,

Figure 3 is a cross-section of Fig. 1 taken along line 3—3 thereof,

Figure 4 is a rear elevational view showing the outlines of the chambers within the bag as well as formula bottles positioned therein, in broken lines,

Figure 5 is an end elevational view of the bag, and

Figure 6 is a cross-section of Fig. 4 taken along line 6—6 thereof.

As shown in Figs. 1, 2, 4 and 5 the formula bag is comprised of a substantially rectangular container which is designated generally by the numeral 10 defined by side walls 11 and 12, bottom wall 13, top wall 14 and end walls 15 and 16. The bag is advantageously formed of a film or sheet of flexible plastic material. It will be understood however that other similar suitable materials may be used for this purpose. The bag is adapted to be carried by means of a carrying strap 34 which may be of conventional type and which is adapted to be adjusted to the desired length by means of adjustment loops 17.

As may be more clearly seen from Figs. 3, 4 and 6 the interior of the bag is provided with chambers 18 and 19 adjacent the end walls thereof. Each of the chambers is defined by an inner and outer wall of flexible sheet material between which a layer of heat insulating material is interposed. It has been found advantageous to employ glass wool for this purpose although it will be understood that other similar suitable thermal insulating material may be employed. Thus, chamber 18 is defined by outer wall or cover 20 and inner wall or lining 22 between which a layer of flexible heat insulation 24 is provided. Similarly, chamber 19 is defined by outer wall or cover 23 and inner wall or lining 21 between which a layer of flexible heat insulation 25 is provided. The end walls 15 and 16 are provided with longitudinally extending slits or openings 26 and 27 respectively to which complementary separable fastening elements such as zippers 35 and 36 are secured. Chambers 18 and 19 are provided with similar longitudinally extending openings the edges of the material of said chambers being secured at the sides of slits 26 and 27 as by stitching 37, whereby independent access into each of said chambers is provided through the longitudinal slits or openings in the end walls. It will thus be seen that each of said chambers defines a thermally insulated compartment which may be opened or closed from the exterior of the bag to permit the insertion or removal of a nursing bottle or similar container. It will further be noted that in view of the remote position of the chambers from each other at the ends of the bag, a substantial physical separation is provided between the chambers themselves thereby additionally preventing any heat transfer from the contents of one chamber to the contents of the other.

The interior of the bag is also provided with an inner lining member substantially co-extensive therewith which comprises a compartment 30 defined by walls 28

and 29, between which a partition wall 31 is interposed to form sub-compartments 32. It will be noted that the lining member extends diagonally across the bag so that it is substantially co-extensive therewith. Access to the liner is provided by means of a slit 33 formed in the top wall 14 of the bag which is similarly closed by means of a separable fastening device such as a zipper 39.

The compartment and the subdivisions thereof formed by the lining to which access is had at the top wall of the bag is adapted to receive additional formula containers or such articles as it may be desired to transport or carry therein. By reason of the diagonal position of liner compartment 30, the complete interior space of the bag is available for use when the end chambers 18 and 19 are empty. It will also be apparent that when either or both of the chambers are in use the space available in the liner for the storage of other articles will only be reduced by a minimum amount.

As may be seen by Fig. 4, chambers 18 and 19 are adapted to receive formula containers such as nursing bottles 38 and are so located that such bottles are spaced from each other at the most remote points permitted by the size and configuration of the bag. The chambers are adapted to receive bottles which are either at high or low temperatures and one chamber may carry a bottle at high temperature while the other is employed for maintaining a bottle and its contents in cold condition. The bottles are insulated from the external atmosphere and from each other. The thermal insulation serves the additional function of a padding to prevent breakage of the fragile containers. The provision of independent closure elements at each end of the bag permits either bottle to be removed or inserted at will without in any manner affecting or disturbing the other bottle or its thermal condition. This feature is very important since such bottles are often carried about for an extended period of time and any opening of a chamber would naturally impair the effectiveness of its thermally insulated condition. As heretofore pointed out, the bag is readily available for the transportation or storage of other articles to substantially the full extent of its interior volume when the chambers are not being otherwise utilized and the storage capacity of the bag is only reduced by the minimum amount when either or both of the chambers are in use. It should also be noted that by providing access to the main or lining compartment by means of an independent opening at the top of the bag, articles may be inserted therein or removed therefrom without affecting the thermally insulated condition of the contents of the chambers.

While I have herein disclosed one embodiment of my invention, it will be understood that the same may be embodied in other forms without departing therefrom.

I claim:

1. A formula bag comprising a substantially rectangular container having a top, bottom, side and end walls, an opening formed in each of the end walls of said bag, a thermally insulated chamber defined by an inner and outer wall of flexible sheet material and a layer of heat insulating material interposed therebetween disposed within said container adjacent each end wall thereof, a longitudinally extending opening provided in each of said chambers, the edges of the material defining each of said chambers, along the openings formed therein, being secured to the end walls of the container along each side of each of the openings in said end walls, a lining member disposed within said bag and substantially co-extensive with the interior thereof, said lining member defining a compartment in the interior of said bag, an opening formed in the top wall of said container providing communication to the interior of said lining compartment.

2. A formula bag comprising a substantially rectangular container having top, bottom, side and end walls, a thermally insulated chamber defined by inner and outer walls of flexible sheet material and a layer of thermal insulating material interposed therebetween secured within said container adjacent each of the end walls thereof, an opening provided in the wall of each of said chambers and an opening provided in each of the end walls of said container in registration with said first mentioned openings whereby an article may be inserted independently into each of said chambers through the openings in said end walls, a lining member defined by walls and substantially co-extensive with the interior of said container secured within said container, and defining a compartment therein, an opening provided in the top wall of said container to permit the insertion of an article into the interior of said compartment.
